UNITED STATES PATENT OFFICE.

JACOB H. COE, OF BRIGHTON, MICHIGAN.

IMPROVEMENT IN DEVICES FOR ELEVATING BUILDING MATERIALS.

Specification forming part of Letters Patent No. 140,116, dated June 24, 1873; application filed May 8, 1873.

To all whom it may concern:

Be it known that I, JACOB H. COE, of Brighton, in the county of Livingston and State of Michigan, have invented a new and useful Improvement in a Device for Elevating Building Material; and I do declare that the following is a true and accurate description thereof, reference being had to the accompanying drawings, and to the letters of reference marked thereon, and being a part of this specification, in which—

Figure 1 is a perspective view of the device, showing the position of the parts at the commencement of elevating a box of material, and in dotted outline the positions when the load is delivered at the second floor of the building in course of construction. Fig. 2 is a partial perspective view from the other side, showing the operation of the weight to return the traversing-carriage with the empty box.

Like letters refer to like parts in both figures. The nature of this invention relates to an improvement in that class of elevating devices which are employed for raising material from the ground to the upper stories of a building in course of construction; having for its object to furnish an apparatus which will not only elevate the material but will also convey it to any point desired and return the empty platform or hoisting-box; and to this end it consists, first, in the employment of the conveyer or traveler H, shown in the patent of Nelson C. Thomas and Jacob H. Coe, dated October 13, 1868, in connection with a portable sectional scaffold for elevating and conveying horizontally the material; and, secondly, in connection with the said devices a counterweight acting through a windlass or drum to prevent the load from sagging out of its horizontal position when elevated until the hoist-rope is slackened, and for returning the empty hoist-box to the proper position for lowering, as more fully hereinafter set forth.

In the drawing, A A represent two sectional standards, the one erected inside and the other outside the walls of the building in course of construction, kept in position by a girt, A'. B is an iron rod stretched between the upper ends of the standards, and C is a traversing carriage or conveyer, whose grooved pulleys a travel on the said rod. It is provided with

a bail, b, a pulley or sheave, c, and a lever-catch, d, which engages with a stop, e, on the rod B, all parts of the said carriage being arranged to operate as described in the aforesaid Letters Patent. D is a box, in which building material is hoisted, and to it one end of the hoist-rope E is attached; from the box it is led up over the sheave c of the carriage; thence to and through a snatch-block, F, secured to the inner standard A under the rod B; thence across to the side of the outer standard and rove through a block, F¹, hanging from it; thence down to a guide-block, F², at its foot; and thence to any suitable hoisting-winch operated by steam or animal power, not necessary to show or describe herein.

It will be evident that if the hoist-rope be wound upon the winch the box will be elevated until a tripper, f, on the rope just above it strikes the lever-catch d and releases the carriage from the stop e, when the carriage will travel along the rod toward the inner standard; but it will also be noticed that the weight of the material will cause the carriage to move more rapidly than is due to the strain of the hoist-rope, and thereby lower the box as soon as the carriage is released from the stop, which, if not overcome, would render the hoisting-gear useless for the purposes of the present invention.

To overcome this objection, and also to enable me to lower the box and stop the carriage at any point on the rod B, I employ a counterweight operating in the following manner: At the foot of the outer standard I place a frame, G, in which a shaft, H, is journaled in suitable boxes, carrying a drum, I, of large diameter, and another, I', of less diameter, and, also, outside the front end of the frame a ratchet, J, with which engages a pawl, K, under which passes a lever, L, which is pivoted to the frame to lift the pawl out of the ratchet and release the drum-shaft. A spring, M, keeps the lever away from the pawl. A tension-rope, N, has one end secured to the bail of the carriage, and is thence led through a pulley-block, O, on the outer standard; thence down through a guide-block, O', at the foot of said standard; thence to the larger drum I, around which several turns are taken and its end secured thereto. On the smaller

drum I' one end of a rope, P, is secured; thence led through a tail-block, Q, suspended from an arm at the upper part of the outer standard, and to its end is suspended a weight, R, sufficiently heavy to counterbalance the box D when loaded. The ropes N and P are so secured to their respective drums that as one is wound up the other is unwound.

The box being on the ground and loaded the hoist-rope is wound up on drum to hoist the box. As soon as the carriage is released from the stop *e* it travels with the box toward the other end of the building. When over the proper point the movement of the hoist-rope is arrested. In the meantime, as soon as the carriage begins its movement, the rope N is drawn by it, revolving the drum-shaft and winding up the rope P on its drum, raising the counter-weight. The pawl holds the drum while the hoist-rope is slackened to lower the loaded box to the floor of the structure when it is either unloaded or the box removed and an empty box hooked onto the rope. The operator by means of the lever now disengages the pawl from the ratchet, when the counter-weight will raise the box to the carriage and draw the latter forward to and lock it with the stop *e*. The hoist-rope being slack the empty box is lowered to the ground by its own gravity, the process being very rapid, it hav-

ing been repeatedly effected, on a hoist of thirty-five feet with a carry of forty feet, in less than a minute, delivering forty-eight bricks and returning an empty box.

The drum I should be provided with a brake to regulate the movement imparted to it by the falling counter-weight. For this purpose the lever L may have a short arm carrying a brake-shoe to press against the perimeter of the drum as soon as the pawl is disengaged by the long arm.

The standards are made in sections the height of a story, (above the lower ones, which are necessarily higher,) so that additional sections may be added as the walls progress, the girt A' being always placed at the top of the whole and the rod B just below it.

What I claim as my invention, and desire to secure by Letters Patent, is—

1. The drums I I' of varying diameters, in connection with the tension-rope N attached to the carriage C, and rope P attached to a counter-weight, R, as described.
2. The combination of the drums I I', tension-rope N, and rope P having counter-weight R with the pawling devices, as described.

JACOB H. COE.
